UNITED STATES PATENT OFFICE.

AUGUST BAUMGART, OF LIND, WASHINGTON.

LIFE-SAVING BOAT.

Application filed January 18, 1923. Serial No. 613,471.

To all whom it may concern:

Be it known that I, AUGUST BAUMGART, a citizen of the United States, residing at Lind, in the county of Adams and State of Washington, have invented a new and useful Life-Saving Boat, of which the following is a specification.

The device forming the subject matter of this application is a life saving boat of that general sort shown in my Patent No. 811,815, granted on Feb. 6, 1906, and one object of the invention is to provide novel means whereby a circulation of air may be secured through the boat, means being provided whereby the port holes in the bow of the boat may be closed automatically, when the water rises about the boat, or when the boat pitches or rolls in a sea-way.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:

Figure 1 shows in longitudinal section, a device constructed in accordance with the invention; Figure 2 is a section on the line 2—2 of Figure 1; Figure 3 is a sectional detail enlarged from Figure 1; Figure 4 is a fragmental longitudinal section wherein parts appear in elevation; Figure 5 is a transverse section showing, in elevation, the parts depicted in Figure 4; and Figure 6 is a cross section on the line 6—6 of Figure 4.

The boat forming the subject matter of this application comprises a bow member 1, a stern member 2, and an inner hull 3 connected by tubular extensions 4 with the bow member 1 and with the stern member 2. An outer hull 6 is provided, and is rotatable about the inner hull 3, the outer hull being adapted to receive the force of the waves, as in my former patent. Rollers 7 are carried by the outer hull 6 and cooperate with the lower portion of the inner hull 3. Rollers 8 are carried by the bow member 1 and the stern member 2 and coact with the end

portions of the outer hull 6. If desired, balls 9 may be interposed between the bow member 1 and the stern member 2, on the one hand, and the ends of the outer hull 6, 60 the balls 9 being located in the lower portion of the boat, within annular flanges 10 which, being carried by the bow member 1 and the stern member 2, coact with the end portions of the outer hull 6 and prevent the entrance 65 of water. Annular members 11 are provided, each annular member comprising a body 12, an outstanding flange 14 and an inwardly extended flange 15. Annular closures 16 are secured at 17 to the body 12, 70 the flange 14 of each annular member being secured as at 18 to the end portions of the outer hull 6. A packing 19 is located between one closure 16 and the inwardly projecting flange 15, balls being disposed between the flange 15 and the closure 16. The balls 20 and the packing 19 coact with the tubular extensions 4, as specified in my prior patent above mentioned.

A shaft 21 extends through one of the tubular parts 4 and carries a propeller 22, the shaft being adapted to be driven by any modern and efficient power. A rudder 23 is carried by a skeg 24 and is operated by a tiller 25 located in the stern compartment 2. 85 Access is had to the stern compartment 2 by way of a hatch 26 which is hingedly mounted at 27 and is held closed by a latch 28. A funnel 29 communicates with the stern member 2 and is under the control of a valve 30, the funnel carrying, at its outer end, a hinged cap 31. Access is had to the bow compartment 1 through a hatch 32 which is hingedly mounted at 33 and is held at 34, by a latch, in closed position. It is to be observed that the bow member 1 is not provided with any funnel, like the part 29. Consequently, the forward hatch 32 may be opened as widely as desired.

As shown in Figure 5, port holes 35 are formed in the sides of the boat and communicate with the bow compartment 1. It is intended that the air shall enter through the port holes 35, circulate through the inner hull 3 and pass out through the funnel 29. 100 The port holes 35 are under the control of hingedly mounted closures 36. A means is provided whereby the members 36 may be closed automatically, when the water rises to a predetermined height about the boat, for 110 instance, whilst the boat is being loaded. It is contemplated, further, that the members

36 shall be closed automatically when the boat rocks or swings in a sea-way.

Having the foregoing considerations in mind, the outer ends of links 37 are pivoted 5 to the closures 36, the inner ends of the links being pivoted to a weight 38 mounted for reciprocation on a well 39, opening through the bottom of the craft, the well constituting a guide for the weight. The well 39 has outwardly extended tables 40 carrying compression spring 41 which serve to cushion the movement of the weight 38, when the same moves downwardly, as hereinbefore described. The weight 38 has a keeper 42 15 wherewith is engaged the bill of a latch 44 fulcrumed intermediate its ends as at 45 on the well 39. At its upper end, the latch 44 has a transverse arm 46. A float 47 is mounted for reciprocation in the well 39 responsive to changes of level in the water in 20 the well. At its upper end, the float 47 is provided with a valve having conical surfaces 48 and 49, the surface 49 being adapted to cooperate with an inclined seat 50 on the well 39, and the surface 49 being adapted 25 to cooperate with an inclined seat 51 on the well. One of the conical surfaces of the valve on the float will always cooperate with the corresponding seat, and, thus, water will 30 be prevented from leaking out of the upper end of the well, when the float 47 is raised sufficiently by the action of the water in the well 39. The valve portion of the float 47 has a stem 54 carrying at its upper end an 35 outstanding projection 52 carrying an inclined cam part 53 adapted to coact with the arm 46 on the latch 44.

A support 55 extends between the upper end of the well 39 and the adjacent portion 40 of the bow compartment 1, and on the support 55, a pendulum 56 is mounted to swing, the pendulum including a weight 57. The pendulum 56 has an outstanding arm 58 provided with a transverse head 59 which is 45 shaped as at 60, to receive the lower portion of the latch 44, the cam edges shown at 60 coacting with the latch in a way to be described hereinafter.

Let it be supposed that the members 36 are 50 open, as shown in Figure 5, and that, due to a loading of the boat or otherwise, water rises in the well 39. Then, the float 47 will be elevated, and the cam portion 53 of the bracket on the stem 54 of the float will coact with the arm 46 of the latch 44, the latch swinging on its fulcrum 45, and the bill 43 of the latch being disengaged from the keeper 42 on the weight 38, whereupon the weight will slide downwardly on the well 55 39 until the weight is received by the cushioning springs 41. As the weight 38 moves downwardly, the links 37 will be carried out-

wardly, and the members 36 will be closed with respect to the port holes 35. The device, in view of the foregoing, affords a 65 means whereby when the boat settles in the water from any fault, the members 36 will be closed automatically.

It may be that the vessel although not loaded deeply, will roll or wallow if there is 70 a sea running, and under such circumstances, it may be desirable to close the port holes 35 automatically. When the vessel rolls, the pendulum 56 swings on its support 55, and the cam edges 60 of the arm 58 on the pendulum, coacting with the lower portion of the latch 44, tilt the latch on its fulcrum 45, the bill 43 of the latch being disengaged from the keeper 52, whereupon the weight 38 will slide downwardly, as aforesaid, the links 37 80 closing the members 36 with respect to the port holes 35.

Having thus described the invention, what is claimed is:—

1. In a device of the class described, a 85 boat having an opening; a door for the opening; weight-actuated means for moving the door to closed position; a latch cooperating with the weight-actuated means to maintain the door in open position; float-actuated 90 mechanism coacting with the latch to release the latch from the weight-actuated means; and a pendulum mounted for swinging movement and coacting with the latch to disengage the latch from the weight-actuated 95 means.

2. In a device of the class described, a 100 boat having an opening; a door for the opening; weight-actuated means for moving the door to closed position; a latch cooperating with the weight-actuated means to maintain the door in open position; means responsive to a settling of the boat in the water for disengaging the latch from the weight-actuated 105 means; and means responsive to a rolling of the boat in a sea way for disengaging the latch from the weight-actuated means.

3. In a device of the class described, a 110 boat having an opening; a door for the opening; means for moving the door to a closed position; mechanism coacting with said means to hold the door in open position; and two devices coacting with said mechanism to disengage the same from said means, one of said devices being float-operated, and the 115 other of said devices being operated by a movement of the boat in the water.

In testimony that I claim the foregoing as my own, I have hereto affixed my signature in the presence of two witnesses.

AUGUST BAUMGART.
